TIE PACK

Barron H. Perry, Long Beach, N.Y.

Application September 25, 1950, Serial No. 186,582

5 Claims. (Cl. 223—83)

1

This invention relates to tie holders and, more particularly, to a holder for holding a plurality of four-in-hand ties in smooth unwrinkled condition.

Among the objects of the invention are to provide a tie holder or pack of the kind described which is light in weight, of rugged construction, simple to construct and operate and which will be of wide utility both in traveling and at home, in holding a number of ties in smooth unwrinkled condition.

Other objects and advantages will be clear from a study of the following description in connection with the drawing.

In the drawing:

Figure 1 is a top plan view of the tie holder with a tie held in place thereon.

Figure 2 is a bottom plan view corresponding to Figure 1.

Figure 3 is a longitudinal cross section to an enlarged scale taken in a plane identified by the line 3—3, Figure 1.

Figure 4 is a perspective view showing the manner in which a tie is folded preparatory to placing it in the holder.

Figure 5 is an exploded view showing in perspective the component parts of the holder, and

Figure 6 is a perspective view of a modification.

Referring in detail to the drawing, the numeral 1 identifies a base or plate of generally rectangular form and which may be of metal, wood, or plastic and provided with lightening holes 2 and 3. At one end the plate is formed as a half-cylinder 1a and is completed into the form of a hollow cylinder by a half-cylindrical form 4 fixed along its edges as by welding or soldering, as indicated at 11, Figure 3, to the corresponding portions or edges of half-cylinder 1a.

The other end of base 1 has two pairs of lugs 5, 6 and 7, 8, secured in outstanding relation to its opposite sides. As will be noted from Figure 5, lugs 5 and 7 are secured in opposite relation, as are lugs 6 and 8. The first pair of lugs 5 and 6 have aligned holes to receive a hinge pin 9. Likewise the second pair of lugs 7 and 8 have aligned holes receiving hinge pin 10, with a smooth fit. The axes of both hinge pins are parallel with each other and with plate or base 1; and are preferably offset equal distances from opposite sides of the plate.

A pair of clamp members 12 and 13 are conveniently of identical form and construction. A description of member 13 will therefore be sufficient. This member may be pressed or stamped from a single sheet of material to form a rounded for-

2

ward edge 13a and a finger piece or portion 13b. Pivot lugs 13c and 13d are conveniently formed integrally with the clamp member and extend outwardly from the member, in parallel relation.

5 The dimensions are such that the distance between the outer surfaces of lugs 13c and 13d is less than the distance between the inner surfaces of lugs 7 and 8 whereby hinge pin 10, when inserted through the aligned apertures in the lugs, 10 mounts the clamp member for limited pivotal movement from the solid line position of Figure 3 to the dotted line position shown thereby. The clamp member 12 is pivoted to lugs 7 and 8 by hinge pin 9 in the same manner as clamp member 13 and may be pivoted through the same angle.

The end of plate 1 adjacent the lugs 5, 6, etc., has a hole 14 therein which is in substantial alignment with confronting circular depressions 15 and 16 formed in the finger pieces 12b and 13b 20 of the respective clamp members. A coil spring 17 passes through hole 14 with a loose fit and has its ends seated in the depressions 15 and 16 to thereby urge the clamping edges 12a and 13a of the clamping members into contact with the opposite sides of the base 1. From Figure 3 it will be clear that both clamping edges may be moved out of contact with the base by pressing finger pieces 12b and 13b together to thereby pivot the members to the dotted line position of Figure 3.

25 Figure 4 shows how a four-in-hand tie T is folded preparatory to positioning it about the holder. The clamp members are pressed together with the fingers of one hand while the other hand is used to slip the center fold of the tie beneath one of the clamp members such as 13, as in Figure 2. This clamp member may then be released while member 12 continues to be held in the dotted line position of Figure 3. The tie is then looped about the cylindrical end and, without 30 pull or tension, its substantially aligned ends are brought beneath the end 12a of clamp member 12, which member is then released. The tie is then smoothly held on and about the holder, as shown upon Figure 3. It will be understood that 35 a number of ties, say two to six, may be so held at the same time in superposed relation.

In Figure 6 there is shown a modification wherein the base 1 may be constructed similarly to the corresponding element of Figures 1 to 5.

40 However the clamp members 18 and 19 while generally similar to members 12 and 13, have relatively laterally offset tabs 18a and 19a, respectively. By this construction each clamp member may be pivoted to open position separately and individually, by pressure exerted be-

55

tween its tab and the base 1. To facilitate this each clamp member is cut away at the corner opposite its tab, as indicated at 18b and 19b. By the preferred construction described; placement of the ties about the holder is facilitated since the folded center of the ties, for example, may be clamped in position and, while thus held, the ends of the tie or ties may be brought around over end 1a and clamped without disturbing the clamp holding the folds. The spring construction and arrangement used with this species is preferably identical with that shown in Figures 1-5 wherein the spring 20 passes centrally through an opening in the base 1 and seats at its ends within recesses in the central end portions of the respective clamp members. By this construction, when one clamp member is opened without the other, the tension in the spring is increased to more firmly hold the other clamp member closed. It will be understood that, with this form of the invention, the clamp members may be simultaneously opened if desired, the same as in the species of Figures 1-5.

I have thus provided a tie holder which is light in weight, easily constructed of inexpensive materials and very useful in holding a number of ties in smooth, unwrinkled condition. The holder, preferably made of plastic, is especially useful in traveling because the ties are held in smooth condition no matter what the position of the holder within a traveling bag or suitcase. The holder is also very useful in the home, where preferred ties may be kept in perfect condition by positioning them about the holder and keeping them in a drawer. It is contemplated that a flexible bag of plastic or other water- and dust-proof material, such as fabric, may be provided to contain the holder and the ties held therein.

As various modifications and substitutions will be apparent after a study of the foregoing description, I desire not to be limited to the precise details of construction shown. To the contrary, it is my desire and intention to reserve all such modifications falling within the scope of the subjoined claims.

Having now fully disclosed the invention, what I claim and desire to secure by Letters Patent is:

1. In a tie holder, an elongated generally rectangular flat base about which a necktie may be doubled, first and second identical clamping members, means mounting said clamping members at one end of said base and upon opposite sides thereof for pivotal movement between their ends about parallel offset axes transversely of said base, corresponding ends of said members being formed with clamping edges engaging respective sides of said base closely adjacent said one end thereof, and a single spring means engaging the other ends of both said members to urge said clamping edges into clamping contact with said base the other end of the base extending beyond said clamping members a distance approximating the length of a folded necktie.

2. In a tie pack, a flat elongated generally rectangular base, a first pair of lugs secured to one end of said base adjacent respectively opposite sides thereof, a second pair of lugs at the same end of said base on the side of said base opposite said first pair of lugs each lug of said second pair being adjacent a respective edge of said base, there being aligned apertures in each pair of lugs defining respective axes offset from said base, said axes being parallel to each other and said base, transversely thereof, a first clamping member mounted by and between said first pair

of lugs for pivotal movement about one said axis, a second clamping member mounted by and between said second pair of lugs for pivotal movement about the other said axis, each said clamping member having a clamping edge transversely of said base positioned between its pivotal axis and the remote end of said base, to engage respective sides of said base closely adjacent said one end thereof, and a single coil spring between said clamping members and urging both said members to move their clamping edges into clamping relation with said base the other end of the base extending beyond said clamping members a distance approximating the length of a folded necktie.

3. A tie pack as recited in claim 3, said other end of the base being in the general form of a cylindrical tube with axis parallel to the pivot axes of said clamping members.

20 4. In a tie pack, an elongated base plate, first and second clamping members, pivot means mounting each said member at the same end of said plate and on respectively opposite sides thereof, for pivotal movement about respective first and second parallel axes, a single spring interposed between and abutting said members at its respective ends to urge the other ends of said members into clamping contact with said plate, each said member having a clamping edge

25 30 35 40 45 50 55 60 65

adapted to engage a respective side of said base plate closely adjacent said one end thereof between its pivot axis and the other end of said base plate, each said clamping member also having a tab projecting rearwardly from its rearward edge, said tabs being relatively offset transversely of the base plate whereby each member may be pivoted independently of the other to release position by pressure between its tab and the plate the other end of the base plate extending beyond said clamping members a distance approximating the length of a folded necktie.

5. In a tie pack, an elongated base plate, first and second clamping members, pivot means mounting each said member at the same end of said plate and on opposite sides thereof, respectively, for pivotal movement about respective first and second parallel axes transversely of said base plate, a single spring interposed between and abutting said members at its respective ends to urge the other ends of said members into clamping contact with said plate, each said member having a clamping edge adapted to engage a respective side of said base plate transversely thereof closely adjacent said one end of the plate and between its pivot axis and the remote end of the plate, each said clamping member also having a tab projecting rearwardly from its rearward edge, said tabs being in superposed relation whereby the clamping edges of both said members may be separated from said plate by simultaneous pressure upon said tabs the other end of the base plate extending beyond said clamping members a distance approximating the length of a folded necktie.
